DISPENSING CLOSURE AND CONTAINER

John W. Starner, Toledo, Ohio, assignor to
 Owens-Illinois Glass Company, a corporation
 of Ohio

Application January 25, 1949, Serial No. 72,579

5 Claims. (Cl. 222—548)

1

My invention relates to containers for talcum or other comminuted materials, and means for dispensing the contents of the container. The invention provides a container which may consist of a molded plastic and which is provided with a closure or cover rotatably mounted thereon for opening and closing a dispensing aperture and which cover may also consist of a molded plastic.

An object of the invention is to provide improved means for rotatably mounting the cover.

A further object of the invention is to provide a construction which permits the contents of the container to be dispensed in an easy and satisfactory manner.

A further object of the invention is to provide improved means for sealing the outlet opening when the cover is in closed position.

Other objects of the invention will appear hereinafter.

Referring to the accompanying drawings:

Fig. 1 is a top plan view of the container with the cover in closed position.

Fig. 2 is a sectional elevation at the line 2—2 on Fig. 1, a portion of the container being broken away.

Fig. 3 is a top plan view, on a smaller scale, of the container with the cover removed.

Fig. 4 is a part sectional side elevation of the container with the cover removed.

Fig. 5 is a side view of the cover.

Fig. 6 is a bottom plan view of the cover and liner.

Fig. 7 is a plan view of the liner.

Fig. 8 is a plan view on a comparatively large scale of the fastener.

Fig. 9 is a side elevation of the same in inverted position.

The container 10 as shown, comprises a rectangular body with vertical sides 11, tapered shoulder portion 12 and a rectangular top portion 13 from which rises a substantially cylindrical dome 14 with a flat horizontal top wall 15. The container is preferably made of a molded plastic such as polystyrene or other plastic, but the invention is not limited to the use of any particular material.

The closure of cover 16 comprises a substantially rectangular flat top and an integral depending skirt 17 which is downwardly flared to align with the tapered shoulder portion 12 of the container. The cover 16 is formed with a cylindrical stem 18 depending from the top at the center thereof. The dome 14 is formed with a central opening 19 through which the stem 18 ex-

2

tends freely to permit rotation of the cover. The container is provided with an elongated discharge opening 21 in the top 15 of the dome, said opening extending in an arc concentric with the central opening 19. The cover 16 is provided with a discharge opening 22 of the same shape as the opening 21 and which is brought into and out of register therewith by rotation of the cover. The openings 21 and 22 when brought into register provide a dispensing aperture.

A liner 24 which may be made of paper or other suitable material, for sealing the opening 21, is mounted within the cover 16 and is glued or cemented to the cover. The liner is formed with an opening 27 in register with the cover opening 22.

The cover 16 is rotatably held in position on the container by a fastener 30 in the form of a disc which consists of resilient sheet metal or material. As shown in Fig. 8, the fastener is formed with parallel slits 31. A square section of the disc is cut away to provide a central opening to receive the stem 18. The construction provides a series of prongs 33 which may be sprung outwardly as shown in Fig. 9. When the cover 16 has been assembled with the container, the fastener 30 is placed in position on the stem 18. The fastener 30 may be introduced through the lower open end of the container before the bottom plate of the container is placed in position. The prongs 33 grip the stem 18 and hold the parts in assembled position. The top 15 of the dome is formed on its under surface with an annular boss 35 against which the fastener disc 30 is held.

When it is desired to dispense a portion of the contents of the container, the top is rotated as indicated by the arrow (Fig. 1) to bring the openings 21 and 22 into register. The rotation of the top is limited in both directions by a stop lug 36 formed on the under surface of the cover and which fits in an arc-shaped recess 37 formed in the periphery of the dome 14. The end walls of the recess 37 form stops which cooperate with the stop lug 36 to limit the rotation of the cover in both directions. In both said limiting positions of rotation of the cover the side edges of the cover are parallel with the sides of the container body, and the cover skirt 17 in register with the tapered walls of the shoulder portion 12.

As shown in Fig. 1, corrugating marks are provided on opposite walls of the rectangular body 11 and on opposite sides of the rectangular cover. These marks are brought into register when the openings are out of register (Fig. 1). The consumer may thereby determine at a glance whether the openings are in or out of register.

Modifications may be resorted to within the spirit and scope of my invention as defined in the appended claims.

I claim:

1. The combination of a container comprising a substantially rectangular body and a rectangular top covering said body, said top including a central cylindrical dome having a diameter less than the width of the top and a marginal horizontal surface surrounding the dome and extending horizontally outwardly to the sides of the container, said dome having a horizontal circular top wall formed with a central opening therethrough, a rectangular cover seated on the top wall of the dome, said cover having a flat horizontal under surface which makes slidable sealing contact with the top wall of the dome, said cover being formed with a depending marginal skirt overlying the marginal horizontal surface of the top, the outer wall surfaces of the skirt being substantially flush with the outer wall surfaces of the container therebeneath, said cover having a central cylindrical stem depending therefrom and extending through said central opening, and a fastener mounted on said stem and holding the cover seated on the container while permitting rotation of the cover, said top and cover having openings brought into register to provide a dispensing aperture when the cover is in one position and moved out of register when the cover is rotated to another position, thereby closing said aperture.

2. The combination of a container comprising a substantially rectangular body and a rectangular top covering said body, said top including a central cylindrical dome having a diameter less than the width of the top and a marginal horizontal surface surrounding the dome and extending horizontally outwardly to the sides of the container, said dome having a horizontal circular top wall formed with a central opening therethrough, a rectangular cover seated on the top wall of the dome, said cover having a flat horizontal under surface which makes slidable sealing contact with the top wall of the dome, said cover being formed with a depending marginal skirt overlying the marginal horizontal surface of the top, the outer wall surface of the skirt being substantially flush with the outer wall surfaces of the container therebeneath, said cover having a central cylindrical stem depending therefrom and extending through said central opening, and a fastener mounted on said stem and holding the cover seated on the container while permitting rotation of the cover, said top and cover each being provided with an arc-shaped opening concentric with said stem and brought into register by rotation of the cover, said cover being formed with a stop lug on the lower side thereof, and the top of the dome being formed with an arc-shaped recess at its outer edge forming a guideway for said stop lug.

3. The combination of a container having a horizontal top wall formed with a central opening therethrough, a cover seated on the container and having a central stem depending therefrom through said opening and rotatable therein, a fastener comprising a flat disc of thin resilient sheet metal, said disc having an opening through which said stem extends and gripping prongs engaging said stem, said top wall of the container being formed with an annular boss on the under surface thereof surrounding said central opening, said boss being downwardly convex in cross section and thereby presenting a rounded bottom surface against which the disc bears and which makes a circular line contact with the disc.

4. The combination of a container comprising a body and a top covering said body, said top including a central cylindrical dome having a diameter less than the width of the top and a marginal horizontal surface surrounding the dome and extending horizontally outwardly to the perimeter of the container, said dome having a horizontal circular top wall formed with a central opening therethrough, a cover seated on the top wall of the dome, said cover having a flat horizontal under surface which makes slidable sealing contact with the top wall of the dome, said cover being formed with a depending marginal skirt overlying the marginal horizontal surface of the top, the outer wall surfaces of the skirt being substantially flush with the outer wall surfaces of the container therebeneath, said cover having a central cylindrical stem depending therefrom and extending through said central opening, and a fastener mounted on said stem and holding the cover seated on the container while permitting rotation of the cover, said top and cover having openings brought into register to provide a dispensing aperture when the cover is in one position and moved out of register when the cover is rotated to another position, thereby closing said aperture.

5. The combination set forth in claim 4, said cover being formed with a stop lug on the lower side thereof, and the top of the dome being formed with an arc-shaped recess at its outer edge forming a guideway for said stop lug.

JOHN W. STARNER.
